UNITED STATES PATENT OFFICE

JOHN Q. SHERMAN AND ALBERT W. METZNER, OF DAYTON, OHIO, ASSIGNEES, BY
DIRECT AND MESNE ASSIGNMENTS, TO THE STANDARD REGISTER COMPANY

MANIFOLDING MACHINE

Application filed October 6, 1921. Serial No. 505,895.

Our invention relates to manifolding machines and more particularly rewind devices for retaining in compact condition either a partial or a full length copy of each transaction on the machine.

In this connection we have developed a number of mechanisms in which the feed of the paper, together with the record strip, is controlled from a pin-wheel feeding mechanism, and after this mechanism has been passed by the record strip, it is wound up on a roll, held and operated inside of the machine case.

In the present invention our object is to drive the rewind mechanism proper by gearing between which and the roll is a friction device. In addition to this, it is our object to provide a uniform length feed for the record strip after it leaves the regular feed, which is preferably a friction feed, and which acts to hold the record strip taut at all times and thus to form a compact roll. Furthermore, this tautness prevents the record strip from interfering with the other strips.

In addition, it is our object to provide a frictional, detachable mounting for the record roll, which mounting is also adaptable to any of the paper rolls of such machines through the intervention of which the record

rewind roll is driven. These objects and other advantages, to be noted, we accomplish by that certain construction and arrangement of parts to be herein-after more specifically pointed out and claimed.

In the drawings.

Figure 1 is a detail side elevation taken inside the side casing showing the new rewind device.

Figure 2 is a detail end elevation showing the friction feed roll or disk on the main feed shaft and the pressure roll for feeding the record strip.

Figure 3 is a detail end elevation showing the mounting shaft for the pressure roll of the feeding mechanism for the record strip.

Figure 4 is a detail end view of the normal tension roll of the main feed for the other strips.

Figure 5 is a section through the friction

drive when it is not provided with teeth to make a gear drive. Figure 6 is a like view showing the device when used with a gear. Figure 7 is a view of the interchangeable element when not a gear.

Fig. 8 is a perspective view showing a roll with end plates and web holding means mounted thereon.

The general type of machine to which our present invention is applied is the pin-wheel type in which the strips of paper delivered from the machine are fed by pin-wheels engaging uniformly spaced lines of perforations along the sides of the strips. As stated, one of the objects of the invention is to provide for the use, in connection with such registers, of a record strip which shall be wound up on a rewind roll instead of being fed from the machine, as are the other strips.

The feed shaft for all the strips is indicated at 1, upon which are mounted the feeding disks 2 with the pins 3 for engaging the perforations. To maintain the proper tension on the perforated strips we provide the pressure roll 49 which is grooved at 50 to clear the pins 3, and is mounted across the case to bear on the paper as it passes the pin wheels. This pressure roll 49 is carried by arms 48 at each end and these arms are fixed to the shaft 47, loosely mounted across the case. Upon this shaft 47 a coiled spring 51 is mounted, tending to exert pressure on the feed rollers, and the end of this coiled spring is passed through a shaft 52 mounted across the case and projecting as at 53.

On the shaft 42 are a pair of arms 54 (one of which is shown in Figure 1) having branches 55 under the influence of springs 56 housed at 57 in the frame. These arms, which are at both ends of the shaft, have branches 58, in which the roller 59 finds support for its spindle. The third branch 60 on these arms lies in position to be rocked upwardly by a finger 61 having a cam end 62 for the said purpose.

Mounted centrally on the feed shaft 1 is a feed disk 63, which contacts with the roller 59, and against which this roller is spring-pressed by the construction last above described.

The writing table curves down from the stripping portion lying over the feed disks, as at 64, and is provided on its under side with an idler roller 65, suitably supported adjacent a slot or cut-away portion in the 5 end of the writing table.

The feed shaft has a gear 66 thereon closely adjacent the side of the frame, and an idler gear 67 meshes therewith. This gear 10 67 meshes with a gear 68 forming part of a friction drive for a roll spindle.

The friction drive will be described below in detail, while for the present the operation of the record rewind will be described. The operator 15 brings the blank record web 4 between the feed disks so as not to engage the pins (it being narrow for this purpose) and down over the writing table over the roller 65, and thence between the feed disk and spring- 20 pressed roller 59 and thence to the rewind roll which is in frictional engagement with the gear element 68. The web is thus held against disk 63, and can be released by rocking the finger 61. Also the paper, if it becomes too 25 tight, will rock the roller 59, against spring pressure at 56.

The feed disk 63, upon revolution by the feed shaft 1, draws over the writing table in conjunction with the spring roller 59 a uniform 30 amount of the record strip at each operation depending on the diameter of the feed roller 63. The gear 68 that revolves the roll on which the paper is accumulated will slip by friction and will slip in an increasing 35 amount, as the rewound or record roll increases in diameter, thus requiring less revolutions to rewind the amount of a normal feed operation.

This arrangement is quite compact and insures a well regulated feed which can be altered by changing the size of the friction feed disk 63.

The friction connection between the rewind shaft or roll known as the rewind and the 45 gear above mentioned will preferably be duplicated with simple modifications to suit in connection with the paper roll that provides the unprinted or blank strip for the record and known as a storage roll. The object of this is to provide a record strip which is taut at all times, so as not to interfere with the normal feed in any way.

One outstanding feature of the friction construction which we will now describe is 55 that the spindle on which a roll may be supported may be screwed into or mounted in it and removed without dismounting the friction device.

In any form of the friction device we provide 60 a support by means of a stud 70 held in place in the frame wall 5 by a screw 71. Over this stud is set a sleeve or bushing 72 having a flange 73 and a grooved end 74.

Over the bushing is set either a gear 68 65 (as for a rewind) Figure 6 or a washer 68^b

(Figure 5) of the same conformation but without teeth, as for merely applying a friction to be applied to the storage roll of the record strip. In case the washer is used we set a pin 76 through the side frame into the 70 washer to hold it against movement. The gear or washer 68 is cut out as at 68^a to engage over the flange on the bushing.

Next to the gear or washer we mount a fibre disk 75 and against it a plate 77 which carries a set of pins 78, and mounted over the pins and the bushing is a cup-shaped disk 79 having holes 80 for the pins.

Next to the disk 79 is mounted a U-shaped piece 81 which is slipped into the groove near 80 the end of the bushing and adjacent the end of the bushing is placed a disk 82 having holes 83 for engaging the pins 78. This disk has a hub portion presenting a pointed tip 84 for entering the hole in the bushing and the end 85 of the stud, which holds disk 82 away from the end of the bushing. The disk has a bar with a threaded hole 85 to receive the roll spindle 86.

Referring to the spindle 86 which is marked 90 86^a for the storage roll it will be noted that on this spindle is to be set the wooden core 87 from which paper is to be unwound, and that it is fitted at its end with plates 88, 89, which plates have holes therein to permit insertion 95 of the spindle. In the instance of the rewind the core is marked 87^a. The hole 90 in the plate nearest the friction device has a flattened side, which provides a driving engagement for the core with the flattened portion 100 91 of the spindle 86^a i. e. in the instance of the storage roll.

Referring specifically to the friction mounting for the record storage roll 6, when the feed shaft is turned the record strip is fed along with a constant tight grasp thereon. The washer 68^b in this case frictionally holds the disk 82, since the bushing flange engages within the depression of the part 68^b and the bushing is pulled into frictional engagement with the said disk. Thus the disk is secured to the plate 77 by means of the pins thereon, which are equipped with nuts to be turned down on the ends of the pins and hold the disk 82 and plate 77 together. The plate 77 is non-rotatably held to the cup-shaped disk which is pressed or rather pulled up against the U-shaped piece set in the bushing groove. The fibre disk and bushing flange engage the washer 68, and the cup and disk assembly 120 are held against the U-shaped piece.

In setting up the storage roll the core 87^a is held in proper position and the spindle thrust through the side of the frame and screwed into the hole in the terminal disk of 125 the friction device. As the roll is unwound the spindle screws down tightly and the core is held so that it cannot move except with the disk 82.

In the instance of the rewind core, the one 130

end plate will be equipped with a pair of holes 92. The gear 68 (Figure 1) will be substituted for the washer 68^b (Figure 6) and the nuts left off the ends of the pins. Also the pin 76 will be omitted.

5 The end of the pins will extend into the holes 92 when the core and spindle are set up as above described, so that the driving of the gear 68 will impart rotation to the bushing and thus to the pin carrying plate 77 and the pins drive the core. The adjustment of tension of the cup is omitted in this instance and the pins do the driving.

10 This friction device is set together easily from inexpensively made parts, which are the same for either a driving friction or a retarding friction with the exception of substitution of a toothed part 68 instead of a smooth part 68 and pinning the smooth part 15 to the casing when it is used.

20 As shown in Figure 8, we provide means for holding the record web tightly on the roll 87^a. Thus the ends 88 and 89 are formed with slots 100 therein, said slots housing a bar 101 that extends across the face of the roll 87 in a suitable channel or groove. The slots 25 are eccentric or tangential to the disk, so that when a strip of paper is passed under the bar 101 and wrapped on the roll, any tendency 30 to slip will pull the bar outwardly of the roll and thus clamp any superimposed turns of the paper very tightly.

35 We do not wish our invention herein to be limited to the exact structure described because of our failure to specifically describe but one set of mechanical equivalents which might be varied without departing from the spirit of the invention set forth.

40 Having thus described our invention, what we claim as new and desire to secure by Letters Patent, is:—

45 1. A friction element for support of a paper roll spindle, comprising a bushing, an element secured to the side frame of a manifolding machine to support said bushing, a controlling element mounted over the bushing and having connections for holding it independent of the bushing, means mounted over the bushing and frictionally pressing 50 against the controlling element, said means comprising in part a pin or pins, and a disk adapted to engage said pins, and to removably engage the spindle of a paper roll.

55 2. A friction element for support of a paper roll spindle, comprising a bushing element having a sleeve portion and a flange portion and means for supporting it in a manifolding machine frame, a controlling element mounted over the bushing and engaging 60 the flange thereon, means mounted over the bushing and pressing against the controlling element, said means having pins thereon, and means for locking a paper roll spindle to said pins.

65 3. A friction element for support of a

paper roll spindle, comprising a bushing element having a sleeve portion and a flange portion, and means for supporting it in a manifolding machine frame, a controlling element mounted over the bushing and engaging 70 the flange thereon, means mounted over the bushing and pressing against the controlling element, said means having pins thereon, and means for locking a paper roll spindle to said pins, comprising a disk mounted 75 over the bushing and engaging said pins, and said disk having a threaded hole to engage the spindle.

4. A friction element for support of a paper roll spindle, comprising a bushing element secured to the side frame of a manifolding machine, a controlling element over the bushing having connections for holding it independent of the bushing, said bushing having a groove therein, a pressure element 80 on the bushing comprising means for pressing against the controlling element, and means for engaging the bushing groove, and said pressure element comprising also pins, and means for detachably locking a paper 85 roll to said pins.

5. A friction element for support of a paper roll spindle, comprising a bushing element having a flange and secured to the side frame of a manifolding machine, a controlling element over the bushing having connections for holding it independent of the bushing, said bushing having a groove therein, a pressure element on the bushing comprising means for pressing the controlling 90 element against said flange, and means for engaging the bushing groove to bear the opposite thrust, and said pressure element comprising also pins, and means for detachably locking a paper roll to said pins, 95 comprising a paper roll spindle, a paper roll, and means on the spindle for non-rotatably engaging the roll, a disk engaging said pins, and mounted on the bushing, said disk having a threaded hole to receive the spindle.

100 6. In a friction element for support of a paper roll spindle, a bushing mounted in the casing of a manifolding machine, means frictionally held on said bushing, and adapted to engage the paper roll spindle, and additional means frictionally held on the bushing and adapted to engage an outside source, as and for the purpose described.
